CLAIM

The ornamental design for a power station, as shown and described.

DESCRIPTION

FIG. 1 is a top perspective view of a power station;
FIG. 2 is another top perspective view thereof;
FIG. 3 is a rear elevation view thereof;
FIG. 4 is a front elevation view thereof;
FIG. 5 is a left elevation view thereof;
FIG. 6 is a right elevation view thereof; and,
FIG. 7 is a top plan view thereof.
The broken line showing of portions of the power station forms no part of the claimed design.

1 Claim, 7 Drawing Sheets
